UNITED STATES PATENT OFFICE

BYRON F. STOWELL, OF SPRINGFIELD, MASSACHUSETTS, ASSIGNEE TO VAN NORMAN MACHINE TOOL COMPANY, OF SPRINGFIELD, MASSACHUSETTS, A CORPORATION OF MASSACHUSETTS

CARRIAGE POSITIONING MECHANISM FOR GRINDING MACHINES

Application filed November 17, 1930. Serial No. 496,178.

This invention relates to machine tools such as grinding machines and particularly to machines of the class in which the relative adjustment between the grinding wheel and the work is accomplished by movement of several superposed slides upon one of which one of the heads is mounted.

The machine will be described in its preferred embodiment as relating to an oscillating grinding machine adapted for the manufacture of races for ball bearings. In machines of this type it is necessary to provide an accurate mechanical feed in a direction at right angles to the axis of the grinding wheel so that the wheel may be fed gradually and progressively against the work as the cutting proceeds. When it is desired to remove the tool from the work, two motions at right angles to each other are necessary. One of these is a rapid motion in the same direction as the slow feed but generally separate from this feed in order to provide quicker motion. The second is at right angles to the first, or in other words parallel to the axis of the grinding wheel. The latter motion serves to withdraw the grinding wheel axially out of the ball bearing ring which is being ground and can only be made after the first motion is completed so that the grinding wheel will clear the annular ground recess in the bearing race. An inverse sequence of motions will occur when the wheel is being placed in position for the start of a grinding operation.

One object of the invention is to provide a single control by which the two rough positioning motions of the tool head may be accomplished. A further object is to provide mechanism which will automatically reset the accurate cross feed whenever the grinding tool is withdrawn from its operative position. A further object is to provide mechanism governed by this same control by which the machine will be automatically stopped by the operation of shifting the tool out of grinding position. A further object is to provide an interlocking control between the various motions so that the machine cannot be operated in a manner to cause injury to the work. Other and further objects will

appear from the following description and claims.

The invention will now be described in connection with the accompanying drawings, in which:

Fig. 1 is a top plan view of the tool head end of a grinding machine embodying my invention;

Fig. 2 is a side elevation thereof;

Fig. 3 is a partial top plan on an enlarged scale showing the parts in a different position of operation;

Fig. 4 is a similar view showing a still different position of operation;

Fig. 5 is a section on line 5—5 of Fig. 4;

Fig. 6 is a partial bottom plan view taken on line 6—6 of Fig. 2;

Fig. 7 is a section on line 7—7 of Fig. 4;

Fig. 8 is a partial rear elevation of the machine; and

Fig. 9 is a detail on line 9—9 of Fig. 7.

The machine is mounted upon a frame 10 which at its tool head end carries ways 11 (Fig. 7). Sliding in these ways is a slide 12 which constitutes the means for moving the tool head in a direction parallel to the axis of the grinding wheel. An accurate limiting position of this slide is determined by means of a bracket 13 (Fig. 2) overhanging the frame and carrying a stop screw 14, so that when the slide is moved the desired amount the screw will abut the frame and stop any further movement.

Mounted in the top of the slide 12 is a sleeve 15 (Fig. 7) having a vertical bore in which rotates a shaft 16. The lower end of this shaft carries a gear 17 meshing with a rack 18 fixed to the frame. By rotating the shaft 16 it is thus possible to move the slide 12 along its ways with a comparatively rapid motion. In order to rotate the shaft, an arm 19 is split as at 20 (Fig. 6) and is drawn together around the shaft by means of a bolt 21. The arm 19 is not directly moved by the operator, but is actuated by connections to be described by a second arm 22 (Fig. 7) freely mounted upon shaft 16. The arm 22 has a cam 23 secured to it by a bolt 24 and serving a purpose to be described later. Bearing upon the top of the cam is a cap 100

screw 25 threaded into the shaft and thus serving to maintain both the arm and the cam in position upon the shaft, while permitting their free rotation in unison. Upon 5 the lower side of the arm 22 is a bracket 26 (Figs. 3 and 6) to which is pivoted at 27 a latch 28. This latch is normally drawn by a spring 29 into the position shown in Figs. 3 and 6 where its end bears against a beveled portion 30 of the lower arm 19. As long as the latch remains in this position, movement of the arm 22 from the position of Fig. 1 to that of Fig. 3 will cause the arm 19 to move with it and through the rack and pinion 10 described will cause reciprocation of the slide 12 in the ways 11.

When the slide 12 has reached the position of Fig. 3, its stop screw 14 is abutted against the frame, preventing any further movement in that direction. This of course stops the movement of the arm 19 and also of the arm 22 which is at this moment connected to the first arm by the latch 28. In order to continue the motion of the upper arm and produce the further positioning movements of the machine which will be described later, it is necessary to disengage the latch 28 from the lower arm. For this purpose the latch is provided at its lower side with a boss 31 connected by a link 32 (Figs. 5 and 6) with a boss or yoke 33 fixed to the lower side of a shaft 34 freely rotatable in the arm 22. At its outer end this shaft has a handle 35 (Fig. 3) secured to it by a key 36 and screw 37. If the handle is turned so that its top moves to the left (as viewed in Fig. 3), the latch 28 will be swung and its end moved beyond the end of the lower arm 19. Motion of the upper arm can then be continued as indicated in 30 Fig. 4.

In order to hold the lower arm 19 in position after it has been disengaged by the upper arm, a latch 38 (Fig. 3) having a hooked portion 39 adapted to engage a latch plate 40 is provided. The latch plate is adjustably mounted by a bolt 41 in an arcuate T-slot 42 formed in a flange 43 of the sleeve 15. The tail 44 of this latch engages a stop 45 carried by the bracket 26. The latch is pivoted at 46 45 (Fig. 6) to the lower arm and is urged into latching position by a spring 47. The latch plate 40 is so adjusted in its slot that the latch will just engage it as stop 14 strikes the frame. Having once been set, it may thereafter be left in its adjusted position until the setting of the stop 14 is changed.

Before considering the remaining functions of the control arms, it is necessary to describe the cross slide mechanism which 60 carries the tool head. Upon the top of the slide 12 are formed ways 50 (Figs. 2 and 8) upon which reciprocates an intermediate slide 51. A nut 52 secured to this slide has threaded into it a screw threaded shaft 53 which is 65 held against axial movement in the slide 12

and which bears a ratchet wheel 54. This ratchet wheel may be rotated automatically in the usual way to cause a slow and accurate cross feed movement of the slide 51. Upon the top of the slide 51 are formed 70 ways 55 in which run a top slide 56. The top slide itself is preferably provided with ways 57 in which a separate motor slide, not shown, is mounted. The tool spindle 59 carrying the grinding wheel 60 is supported in 75 this slide 56.

To the rear end of the intermediate slide 51 is secured a plate 61 (Fig. 3) upon which the nut 52 may conveniently be mounted. The plate 61 also carries a stop screw 62 80 positioned to lie in the path of the top slide 56 and limit its outward movement. The plate also is apertured to permit the passage of a stud 63 secured to the top slide and bearing stop nuts 64 serving to limit travel of 85 the top slide in the opposite direction.

A stud 65 is secured to the top slide and has a fixed collar 66 and a movable collar 67 pressed toward it by a spring 68 compressed between the movable collar 67 and a fixed 90 collar 69. The end of an arm 70 pivoted at 71 upon a bracket 72 extending from the slide 12 is apertured to receive the stud 65 and is positioned between the collars 66 and 67. The arm 70 is formed as a bell crank 95 and its other end is provided with a flat surface 73 against which the cam 23 is adapted to bear. As the cam presses the adjacent end of the bell crank to the left as viewed in Fig. 3, the other arm of the bell crank 100 will exert a pull on the slide 56 and will cause it to be drawn outwardly toward the stop 62. The cam is provided with an arc shaft slot 74 through which passes the bolt 24 previously mentioned, thus permitting the 105 cam to be adjusted in any desired angular position. In order to keep the surface 73 pressed toward the cam, a spring 76 is provided, compressed between a fixed collar 77 and a movable collar 78 on a rod 79 secured 110 to the intermediate slide 51.

Mechanism is also provided for resetting the slow cross feed given by the shaft 53 when the slides are moved to their inactive position. For this purpose a gear 80 (Fig. 2) is 115 secured to the shaft 53 and has meshing with it a train of gears 81, 82 and 83. Adapted to mesh with the last of these gears is a rack 84 pivoted at 85 to the frame so that it may oscillate between a position meshing with the gear 83 and a position just below it. A lifter 86 is pivoted to the frame at 87 below the rack and has a rod 88 connected to it which passes through a bracket 89 projecting downwardly 120 from the slide 12. Within a recess in the bracket are fiber blocks 90 and 91 (Fig. 7) encircling the rod 88 and pressed together by a spring 92 held in place by a cap 93. The blocks bear against the rod with just sufficient force to exert a frictional drag upon it. 125

When the slide is moved to the left in Fig. 2, the lifter 86 will be moved in a counterclockwise direction and will permit rack 84 to descend. When the slide moves back to its inactive position, the lifter will be rotated in the opposite way and will raise the rack so that it will mesh with the gear 83. Since this gear moves with the slide 12 and the rack is stationary, a rotation will be imparted to the shaft 53 on a rearward motion of the slide. This is sufficient to cause the amount of forward rotation given to the shaft 53 during the feeding movement to be compensated for.

It will be noted from the description above that a single motion of the handle 35 from the position of Fig. 4 to that of Fig. 1 will first move the grinding wheel in a direction at right angles to its axis to disengage it from the work piece which has just been ground, and then will move the wheel in the direction of its axis to withdraw it from the locality of the work piece and permit the latter to be removed without hindrance. To remove the work piece, however, it is necessary to stop its rotation and also the oscillation of the head which carries it. This rotation and oscillation may be imparted to the work head by any suitable mechanism operated from a main shaft 190 (Fig. 9). A suitable mechanism is shown in the patent to Van Norman, No. 1,722,691, July 30, 1929, the shaft 190 in the present case corresponding to the shaft S of the patent. Mounted upon the shaft 190 is a tight pulley 191, a loose pulley 192, and a brake disk 193. A belt from any suitable power source passes over the pulleys, being maintained under the control of a belt shifter 94 carried by a sliding rod 95. A brake 96 is also carried by the rod 95 so that when the belt is shifted to the loose pulley not only will the driving force be cut off from the shaft but a braking force will be applied to bring it to rest quickly.

The rod 95 is constantly urged towards the left in Fig. 9 by a spring 97. An arm 98 is secured to a short pivot shaft 99 and has a pin and slot connection 100 with the rod. Also secured to the shaft 99 is an arm 101 joined by a link 102 (Fig. 7) with a treadle 103. By depressing the treadle, the rod 95 is shifted in a direction to cause the belt to be moved onto the tight pulley. When once depressed it is held in that position by a rod 104 sliding in the frame and urged to the left in Fig. 7 by a spring 105 compressed between the frame and a collar 106 on the rod. In its left hand position the end of the rod projects beyond the side of the arm 101, the motion of the rod being limited by contact of the collar with the face of the arm (Fig. 9).

The end of the rod 104 remote from the collar carries a rounded disk 107 (Fig. 7) which lies adjacent the lower end of an arm

108 secured to a shaft 109 journaled in a bracket 110 secured to the slide 51. A second arm 111 secured to the shaft is fastened at its upper end to a rod 112 projecting from the slide 56. As the latter slide is moved to free the grinding wheel from its work, the disk 107 is struck by the arm 108 and pushed far enough to the right in Fig. 7 to withdraw the end of rod 104 from its position beside the arm 101. The rod 95 is thus freed for motion under the influence of the spring 97 in a direction to shift the belt to the loose pulley 92. By this mechanism the power to the machine is placed under the control of the operating handle 22. A single swing of this handle moves the grinding wheel transversely to free it from the work, shuts off the power, moves the grinding wheel longitudinally, and resets the slow feeding mechanism.

What I claim is:

1. A grinding machine having a pair of slides at an angle to each other, a single handle movable through an arc, mechanism operable by the handle while moving through one portion of said arc for moving one slide, and mechanism operable by the handle while moving through another portion of said arc for moving the other slide. 85

2. A grinding machine having a work head, a first slide movable toward and away from the work head, a second slide movable upon the first at an angle thereto, a tool head carried by the second slide, a handle pivoted for rotation upon the first slide, mechanism operable by the handle during one portion of its rotation for moving the first slide, and mechanism operable by the handle during another part of its rotation for moving the second slide. 95

3. A grinding machine having a work head, a first slide movable toward and away from the work head, a second slide movable upon the first at an angle thereto, a tool head carried by the second slide, a handle pivoted for rotation upon the first slide, a stop limiting the motion of the first slide, mechanism operable by the handle during the first part of its rotation for moving the first slide, a device carried by the handle for releasing it from the first slide moving mechanism, and mechanism operable by the continued rotation of the handle for moving the second slide. 100

4. A grinding machine as claimed in claim 3 in which the releasing device carried by the handle comprises a manipulable element rotatable to cause release. 110

5. A grinding machine comprising a frame, a slide mounted on the frame, a second slide mounted on the first at an angle to it, a shaft journaled in the first slide, a rack and pinion connection between the shaft and the frame, a handle rotatable on the shaft, pawl mechanism releasably connecting the handle to the shaft, a bell crank pivoted on said slide, a 120

65 which lies adjacent the lower end of an arm 125

cam carried by the handle acting on the bell crank to rock it upon its pivot, and connections between the bell crank and the second slide.

- 5 6. A grinding machine comprising a work head, a first slide, means for moving the first slide towards and away from the work head, a second slide movable upon the first slide at an angle thereto, a third slide movable upon 70
10 the second slide, a tool head carried by the third slide, mechanism for moving the third slide upon the second slide to place the tool head in or out of operative relation with the work head, means for moving the second slide 15 upon the first slide with a slow tool-feeding movement, and mechanism automatically operable upon the movement of the first slide away from active position to reverse the slow tool-feeding movement of the second slide and 20 return it substantially to its original position.

7. A grinding machine having rotary work holding and wheel carrying heads, means for moving one head relatively to the other in directions substantially parallel with and 25 right angularly to the axis of its rotation, slow feeding mechanism for moving said head in one direction and a single lever controlling, through progressive movements thereof, mechanisms operable to effect a 30 rapid withdrawal of said head in each of its directions of movement and to impart an accelerated reverse movement to said feeding mechanism.

8. A grinding machine having rotary work 35 holding and tool carrying heads, means for moving one head relatively to the other in directions substantially parallel with and angularly to the axis of its rotation, slow feeding mechanism for moving said head in 40 one direction, power means including a driving shaft, and a single lever controlling

through progressive movements thereof mechanisms operable to effect a rapid separation of the heads and impart an accelerated reverse movement to said feeding mechanism and to discontinue the power means and to retard and stop the free rotation of said driving shaft.

9. A grinding machine or the like having rotary work holding and tool carrying heads, 75
means for supporting one of said heads for movement relative to the other in two directions, one substantially parallel to and the other substantially at right angles to the axis of rotation of the head, mechanism for moving said head at a slow rate of feed in one of said directions, a progressively movable member, and mechanism actuatable by progressive movement of said member for moving said head in a sequence of quick acting movements in both of said two directions. 80

10. A grinding machine or the like having rotary work holding and tool carrying heads, means for supporting one of said heads for movement relative to the other in two directions, one substantially parallel to and the other substantially at right angles to the axis of rotation of the head, mechanism for moving said head at a slow rate of feed in one of said directions, a progressively movable member, mechanism actuatable by progressive movement of said member for moving said head in a sequence of quick acting movements in both of said two directions, and separate mechanism operable through movement of said head in one of said directions of travel to effect a reversed and accelerated movement to said slow feeding mechanism. 90
95

In testimony whereof I have affixed my signature.
